UNITED STATES PATENT OFFICE.

THOMAS NATHAN RUSSELL AND JOHN W. BERNBAUM, OF CHICAGO, ILLINOIS, ASSIGNEES TO CHICAGO-CLEVELAND CAR ROOFING COMPANY, OF CHICAGO, ILLINOIS, A CORPORATION OF ILLINOIS.

CAR-ROOF.

1,202,104.

Specification of Letters Patent. Patented Oct. 24, 1916.

Application filed July 18, 1916. Serial No. 109,974.

To all whom it may concern:

Be it known that we, THOMAS NATHAN RUSSELL and JOHN W. BERNBAUM, residing at Chicago, in the county of Cook and State 5 of Illinois, citizens of the United States, have invented a new and useful Improvement in Car-Roofs, of which the following is a specification.

The invention relates primarily to metal 10 car-roofs of the type set forth in the Russell Patent 1,177,144, issued March 28, 1916, although it may be applicable to other car-roofs. And it has for a main object the providing of a supplementary moisture-ex- 15 cluding and sheet-edge stiffening sub-sheet underneath the sheet-edges transverse of the car, and dispensing with the necessity for an eaves-flashing under the eaves ends of the sheets and carlines; and the invention 20 has for further objects such other improvement in structure or function as may be found to obtain in the devices hereinafter described or claimed.

With such objects in view, the invention 25 consists in the parts and combinations thereof hereinafter set forth and claimed, with the understanding that the several elements constituting the same may be varied in proportion and arrangement without departing 30 from the nature and scope of the invention defined in the claims.

In order to make the invention more clearly understood there are shown in the accompanying drawings means for carrying 35 the same into practical effect, without limiting the improvements, in their useful applications, to the particular constructions which, for the purpose of explanation, have been made the subject of illustration.

40 In the said drawings:—Figure 1 is a plan view of a portion of a car roof embodying the invention. Fig. 2 is a side view of a portion of the same, on an enlarged scale. Fig. 3 is a vertical transverse section of a 45 little more than one-half of the roof on line III—III of Fig. 1. Fig. 4 is a similar section on an enlarged scale of the eaves portion of the roof. Fig. 5 is a longitudinal section, on a still larger scale of the ridge 50 portion of the roof, taken on line V—V of Fig. 3. Fig. 6 is a vertical longitudinal section, through the ridge at one end of the roof. Fig. 7 is a vertical longitudinal section on line VII—VII of Fig. 1. Figs. 8, 55 9 and 10 are detail views of one-half of

one of the sub-sheets. Fig. 11 is a horizontal section on line XI—XI of Fig. 4. Fig. 12 is a perspective detail of an eaves end of one of the sub-sheets, and Fig. 13 a section on 13—13.

The construction of the roof frame and roof sheets is or may be of the following character: Referring to the drawings, 1 indicates the side plates of the roof frame, consisting of Z-bars. The top member of the Z-bar serves as a rest for the end of the carline. To the vertical member or web are attached on the outside the overlapping vertical ends or flanges of the roof sheets and carlines, and on the inside are attached the upper ends of the side sheathing; and the lower member or flange of the side plate extends outward beyond the other parts of the roof to serve as a protecting means for the ends of the roof sheets and carlines and take the place of a fascia, or to form a place of attachment for the upper ends of the side-braces of the car.

2 indicates the side sheathing attached to the side plates by bolts 3 (Fig. 3), and 4 is the ridge pole consisting preferably of a U-shaped channel iron having side flanges 6, which are attached to the carlines by rivets 35 or other suitable means, such as electric spot-welding. The ends of the ridge pole are supported by end plates 5, through any suitable connection, one of such end plates being indicated at 5 in Figs. 3 and 6. At its ends the ridge pole is formed on its upper side with an offset 7 to receive the top flange 8 of the end plate and leave the top surface of the ridge pole and end plate coincident with the bottom surface of the roof sheet (Fig. 6). The ridge pole is attached to the flange 8 by rivets 18 which pass through the flanges 6.

The carlines are shown at 9, each formed upon an arc or curve and adapted to extend from side plate to side plate across the ridge pole 4. The body of the carline consists of a horizontal web 11, formed at its sides with upstanding flanges 12, which terminate in curved flanges 13 extending outward away from the carline in directions longitudinal of the car, and then downward, the said curved flanges 13 approximating a half circle in contour and extent. At its ends the carline terminates in vertical flanges 10 depending over and at the outer sides of the side plates, each of said flanges 110

10 being perforated by a hole 17 for a rivet 15 which secures the carline to the side plate. The flanges 12 and 13 terminate at the upper part of the flange 10, and in line 5 with them the flange 10 confines the adjacent ends of the downturned eaves flanges of the roof sheets against the side plate 1, said flange 10 being recessed (Figs. 4 and 11) to fit over such sheet-flange ends.

14 indicates the purlins, one or more of which is or are arranged underneath the carlines and roof sheets and between the ridge pole and side plate, at each side of the car. The purlin is supported at its ends by 5 the end plates 5, to which it is or may be attached by rivets. At these points the end of the purlin is formed on its upper side with an offset to receive the top flange 8 of the end plate and leave the top surfaces of 10 the purlin and end plate coincident with the bottom surface of the roof sheets, in the same manner as has been described with reference to the ridge pole. The purlin is or may be of the same form as the ridge pole, 5 with side flanges 19. The purlin is attached to each carline 9 by rivets 20 which pass through the flanges 19 and through the web 11 of the carline. Electric spot-welding may be used for these attachments of the 10 purlin or ridge pole, but it is preferred to use attaching means which can draw the purlin more or less toward or against the under side of the carline, to press the roof sheets firmly into place.

5 Each end plate consists of an angle iron 5, L-shaped in cross section (Fig. 6), the top horizontal flange 8 of which is arched to conform to the contour of the roof and which supports the end portion of the end 10 roof sheet 21. The inner transverse edge of this roof sheet is flanged, as hereinafter described with reference to the intermediate roof sheets, and its outer transverse edge is flanged down over the end fascia 22 as shown at 23 (Fig. 6). The side and end sheathing may be constructed with the boards running horizontally, or vertically, as may be preferred.

The carlines 9 are preferably formed by dies, from steel of suitable strength and malleability. At each end the carline has its bottom web 11 formed with horizontal seats 26, the metal of the web being pressed downward out of the normal arc of the carline for such purpose. These seats 26 rest and fit on the top horizontal members of the side-plate Z-bars, to which they are secured by rivets 27.

28 is the roof sheet (Fig. 7) which is formed on an arc or curve to correspond with the carlines and to extend across the car, over the ridge pole and over the side plates 1. At its ends it is formed with depending vertical flanges 29 which fit over and against the side plates 1, to which they

are secured by bolts 30. The front and rear ends of the flanges 29 fit under the lateral recesses of the flanges 10 of the carlines. The body of the roof sheet is or may be suitably corrugated to increase its thickness 70 and weight-sustaining capacity. Transverse corrugations 31 are illustrated arranged in the spaces between carlines, and may be of suitable number. As shown in Fig. 1 the corrugations are made relatively 75 long so as to extend across the ridge pole and to a considerable distance at each side thereof. Along each side and extending substantially from side to side of the car the roof sheet is formed with an S-flange 32 of 80 such shape and extent that the lower bend or shoulder 33 may brace firmly against the flange 12 of the carline, and that the upper bend or shoulder 34 braces in the opposite direction tightly against the inner surface 85 of the lip of the curved flange 13 of the carline (Fig. 5). The arrangement is such that the bottom surfaces of the roof sheet and of the carline are or may be flush with one another, both resting on the ridge pole, and 90 on the purlins 14.

37 is the running board (Figs. 2 and 3) the parts of which are connected by bolts 38 with the horizontal flange of an angle iron 39. The vertical flange of the latter is secured by bolts or rivets 40 to the vertical legs of angle irons 41, and the feet of the latter are riveted at 42 directly to the web plate 11 of the carline between the vertical flanges 12 of the latter. Such a connection 100 as is above described is or may be effected between the running board and each of the carlines. The roof plates at the ends of the car omit one of the S-flanges as already described.

The roof above described is not the present invention, but is involved (or its equivalent) in combination with the features of improvement herein described.

44 is a sub-sheet (Figs. 8, 9 and 10) which 110 is preferably narrow relative to the roof sheets, but is a little wider than the base of the carline, and is arranged beneath the carline and beneath portions of the roof sheets. It is of such shape as to conform with the 115 contour of the car roof and preferably extends as a single sheet from eaves to eaves of the roof, being formed at its ends with depending flanges 45 which fit against the outer faces of the side plates. Such a sub-sheet is provided under each of the carlines, and it is further formed with up-turned side flanges 46 which preferably extend over the sheet but lie nearly flat on the same so as 120 not to occupy much vertical space but sufficiently to catch and hold and guide downward to the outside of the car any water which may in any manner enter through the joints between the carlines and the roof sheets. These flanges 46 are pressed down 125 130

- flat upon the depending flange 45 (Fig. 11) and the depending flanges 29 of the roof sheet rest against them, the roof sheets being confined by the depending flanges 10 of the carlines. This arrangement leaves vertical spaces or drainage openings 47 through which any seepage collected as above described may pass down to the outside of the car. The said sub-sheets are suitably held in place, preferably by riveting to the base flanges of the carlines, and are also supported by the longitudinal members of the roof, including the purlins when the roof comprises such members (Fig. 3). 10
- 15 When the roof sheets are formed with transverse corrugations 31 the flanges 46 of the sub-sheets are arranged to fit within said corrugations (Fig. 7) thus allowing the whole body of the sub-sheet to fit closely against the under sides of the roof sheets. The seats 26 of the carlines merely depress the middle portion of the sub-sheet underneath them, the thinner metal of the sub-sheet conforming or accommodating itself 20 to such overlying portion of the eaves ends of the carline; and such depressing of the middle of the eaves ends of the sub-sheets, together with the tapered compressing of their lateral flanges as they approach the 25 eaves, serves further to facilitate the drainage through the above mentioned spaces 47. The conformation of the eaves ends of the sub-sheets is best shown in the perspective view, Fig. 12.
- 30 35 What is claimed is:
1. In a metal car-roof, in combination: externally-exposed channel carlines having upwardly extending side-flanges and arched from side to side of the car; laterally-flanged and likewise arched metal roof-sheets engaged with said carline-flanging and having their body portions substantially flush with the base of the carline-channels and provided with corrugations adjacent and parallel to the mutually engaged sheet and carline flanges; sub-sheets closely applied under the carline-channels and sheet-flanging and having upwardly and inwardly rebent edges engaged within the said sheet corrugations and 40 having downwardly bent end-flanging extending over the car-side; and purlins se- 45
  2. A metal car-roof sub-sheet having upwardly and inwardly rebent lateral flanges and downwardly rebent end-flanging, said lateral flanges being spaced above the main body of the sub-sheet and flattening down toward and into the end-flanging portion 50 thereof; said sub-sheet being adapted to be applied directly under the transverse car-roof seams formed by mutually engaged carlines and roof-sheets; substantially as specified. 55
  3. In a metal car-roof, in combination: externally exposed metal carlines laterally flanged and projecting above the roof-level; and roof-sheets laterally jointed with said flanges, along the outer sides of the carlines; 60 and sub-sheets having lateral upwardly and inwardly turned flanges and arranged underneath said carlines and spanning said joints and extending over the sides of the car; substantially as specified. 65
  4. In a metal car-roof, in combination: externally-exposed channel carlines having upwardly and outwardly extending side-flanges and arched from side to side of the car; laterally-flanged and likewise arched 70 metal roof-sheets having their flanges compressed under said carline-flanging and having their body portions substantially flush with the base of the carline-channel; sub-sheets closely applied under the carline-channels and sheet-flanging and tending to hold said sheet-flanges in compression under said carline-flanges; and longitudinal members secured under said sub-sheets and carlines and supporting said roof-sheets; sub- 75 substantially as specified. 80
